CHARLES C. MAURER AND NORMAN D. VEA, OF DOVER, OHIO, ASSIGNORS TO DOVER MANUFACTURING COMPANY, OF DOVER, OHIO, A CORPORATION OF OHIO

SWITCH PLUG

Application filed May 5, 1930. Serial No. 449,855.

This invention relates to improvements in switch plugs with particular reference to terminal plugs or electrical cables employed to supply current to electrically heated sad irons and other tools.

The object of this invention is to provide a form of plug more durable than those heretofore used under similar conditions.

Further objects are to provide a form of construction in which the switch operating piece will not become heated, in which the operating piece will be in a position for instant and convenient manipulation, in which the switch itself and its contacts will be protected from excessive heat, in which the cord or cable can be so connected that there will be minimum interference with the manipulation of the tool or with the operation of the switch, and in which all of these objects can be accomplished with minimum expense and a switch produced which will be of maximum durability and reliability.

In the drawing:

Figure 1 is a side view of a switch plug employing my invention.

Figure 2 is a view of the same with one side portion of the casing removed and the remainder shown in section to disclose the terminals, switch members, etc.

Figure 3 is a section drawn generally to line 3-3 of Figure 2.

Figure 4 is a detail view of the stationary contact terminal of the switch and associated parts viewed at right angles to their position as illustrated in Figure 2.

Figure 5 is a side elevation of a sad iron showing the operative position of the plug.

Like parts are identified by the same reference characters throughout the several views.

The improved plug has body members 10 and 11 formed of insulating material divided substantially in a plane common to the axis of the cord receiving socket 13 and the operating piece or lever 14. The plug portion 15 is also of insulating material and is held to one end of the body portions 10 and 11 by a metal jacket 16 having arms 17 received in recesses in the sides of the body portions 10 and 11 whereby the three insulating mem-

bers may be held together by screws 18. The terminal socket members 20 and 21 are respectively mounted partially in the members 10 and 11, said members being suitably recessed to receive the attached ends of the sockets. At their other ends these socket members extend into the cylindrical cavities formed in the plug portion 15 in a position to receive the terminal posts of an electrical heater in the ordinary manner.

One of the lead wires 24 of the cord 25 is connected to the screw 22 which serves as a binding post for the socket terminal 20. The other lead wire 26 is connected to the switch mounting 27 by a screw 28 which also serves as a binding post.

The switch mounting 27 has a circularly enlarged portion 28', through the center of which a pivot pin 29 is passed and to which the switch lever 14 is pivoted. An independently movable switch arm 30 is also pivoted to the pin 29, this switch arm being preferably forked to receive the lever 14 between them as clearly shown in Figure 3. At each side a helical tension spring 32 is secured to the cross pins 33 and 34, mounted in the lever 14 and switch arm 30 respectively and extending laterally to points where the springs may swing from side to side, when lever 14 is being manipulated, without contacting with the mounting 27. The body members 10 and 11 are interiorly recessed to provide a cavity of sufficient size for the switch and mounting 27 and springs 32.

The socket terminal 21 is connected by the screw 22' with a stationary switch terminal 35 which preferably carries a contact portion 36 (Fig. 4) and an off set contact portion 37 both of which may be simultaneously engaged by a contact roller 38 carried by the switch arm 30. The roller is preferably journaled upon the pivot pin 34.

From the foregoing description the operation of the switch will be obvious. Movement of the operating piece or lever 14 toward the right from its position as shown by full lines in Figure 2 to the dotted line position will carry the springs 32 across the central plane indicated by the line 3-3 in Figure 2 to a point where the reaction of the

5 springs 32 will retract the switch arm 30 to the dotted line position with the roller in contact with the recess body walls of insulating material. Movement of the lever 14 in the opposite direction will again carry the springs across the central plane whereupon they will swing the contact roller 38 to the stationary terminal members 36 and 37. If the socket members 20 and 21 are then in engagement with the terminal posts of a heating unit, the 10 circuit will be closed through the heating unit from terminal socket 20 to terminal socket 21 and through the switch.

15 The exposed end of the switch lever 14 being covered by a sheath of insulating material 38, it is obvious that the electrical current cannot follow lever 14 to the exterior and all of the associated parts are completely insulated by the body members 10, 14 and 15 from 20 the socket terminal 20 and its associated electrical connections. The switch proper, including the springs 32, are located at the outer end of the body and the insulating material composing the body members 10 and 11 25 are also non-heat conductive.

30 Material heat conduction can take place only through the limited areas or paths for such conduction afforded by the stationary contact members 36 and 37 whereby only a slight number of heat units may reach the 35 roller 38 and associated parts. It will, therefore, be obvious that the movable parts of the switch mechanism will have substantially the same durability that they would have if they were not employed for connecting up the circuit of an electric heater or otherwise exposed to the high temperatures of such heaters.

40 The location of the cord at one side of the central axis of the switch plug and in an oblique position, (preferably at approximately a 45° angle to said axis) tends to keep the cord at one side of the field of operations of a sad iron or other tool to which the plug 45 may be connected, since very few movements of the tool will be in line with the portion of the cord which is connected to the plug.

50 It will be observed that the switch socket 40 extends across the central transverse plane of the body indicated by the line 3—3 in Figure 2 and that the switch and also the switch operating lever 14 swing across this plane when moving from closed to open position. When the plug is in the oblique position in 55 which it is shown in Figure 5 the lever will be plainly visible, whereby it can be determined by inspection whether the switch is in the open or closed position. By allowing the plug cavities 42 and 43 to ventilate along the socket terminals 20 and 21 to a cord receiving recess or socket at the side of the plug the heat is carried away without reaching the switch cavity 42. Cavity 43 communicates with the upper end of cavity 42 60 through the transverse groove 44.

70 While it is not novel to employ independently movable switch actuating levers and switch arms which are connected by tension springs moving across a pivot line common to the lever and switch arm, yet such switch operating mechanism has not heretofore 75 been thought adaptable for switch plugs associated with electric heaters because the heat tends to take the temper out of the springs and shorten the life of the mechanism. 80

85 But we have found that by isolating the switch mechanism from the hot part of the plug, the durability of such a switch can be increased more than three fold and it therefore becomes entirely practical to employ helical spring connections in the switch mechanism above described.

89 We claim:

90 1. A switch plug for electric heaters comprising the combination of an insulating body having a switch recess at one end and a plug portion at the other end, each located across the axial center line of the plug, a switch in the switch recess having an operating lever extending through an end slot in the body said plug portion being provided with vented electrical terminals and the body having lateral electrical connections controlled by the switch, said switch 95 and its operating lever being each arranged to swing to open and closed positions across an axial central plane transverse to that of lever and switch movement, and a stationary contact member for the switch at the inner 100 end portion of the switch recess in electrical connection with one of the socket terminals.

105 2. A switch plug for electric heaters comprising the combination of an insulating body having a switch recess at one end and a plug portion at the other end, each located across the axial center line of the plug, a switch in the switch recess having an operating lever extending through an end slot in the body, said switch and its operating lever 110 being each arranged to swing to open and closed positions across an axial central plane transverse to that of lever and switch movement terminal socket members in the plug, and a stationary contact terminal for the 115 switch at the inner end portion of the switch recess electrically connected with one of the socket terminals, said body having an oblique current supply connection in permanent electrical connection with the switch 120 and the other socket terminal.

125 3. A switch plug for electric heaters comprising the combination of an insulating body having a switch recess at one end and a plug portion at the other end, each located across the axial center line of the plug, a switch in the switch recess having an operating lever extending through an end slot in the body, said switch and its operating lever 130 being each arranged to swing to open

and closed positions across an axial central plane transverse to that of lever and switch movement, and a stationary contact terminal for the switch at the inner end portion of the switch recess, socket terminals located in the plug portion, one electrically connected with said stationary contact terminal, electrical supply connections extending through an opening in one side of the body and connected with the other plug socket terminal and with the switch respectively, said body being in two parts separable in a plane substantially co-incident with that of the lever and switch movement and having the plug portion connected with its opposite end by a metal sheath in coupling relation to the body members said metal sheath being secured to the respective ends of the body at points laterally offset from the cavities therein.

4. A switch plug having a body provided with a switch cavity at one end and a plug portion at the other end, said plug portion containing socket terminals, and a body having a laterally extending cord receiving socket serving as a ventilating passage in communication with space about said socket terminals whereby said switch cavity may be isolated and heat insulated by the body.

5. A switch plug having a body provided with a switch cavity at one end and a plug portion at the other end, said plug portion containing socket terminals, and a body having a laterally extending cord receiving socket serving as a ventilating passage in communication with space about said socket terminals whereby said switch cavity may be isolated and heat insulated by the body, said switch cavity having a contact terminal at its inner end connected with one of the socket terminals and also having a pivoted switch arm adapted for contact with said terminal, and an operating lever fulcrumed at the axis of the switch arm and intermediately connected with the switch arm by tension springs adapted to swing the switch arm across a central plane which includes the pivot axis when the lever is swung across such plane.

6. In a switch plug mechanism for electric heaters, the combination with a body portion having an isolated switch receiving socket, socket terminals substantially heat insulated from said socket, one of said terminals having a forked stationary contact member at the inner end of said socket, and a switch mechanism in said socket provided with a roller adapted to be moved into and out of engagement with said forked contact member.

7. In a switch plug mechanism for electric heaters, the combination with a body portion having an isolated switch receiving socket, socket terminals substantially heat insulated from said socket, one of said ter-

minals having a forked stationary contact member at the inner end of said socket, a switch mechanism in said socket provided with a roller adapted to be moved into and out of engagement with said forked contact member, and means for ventilating the space in which the socket terminals are located, laterally of the switch receiving socket.
